A. L. HAWKESWORTH.

DRILL.

APPLICATION FILED NOV. 21, 1921.

1,423,849.

Patented July 25, 1922.

Inventor:
Arthur L. Hawkesworth
By Harry A. Baum
Attorney.

UNITED STATES PATENT OFFICE.

ARTHUR L. HAWKESWORTH, OF BUTTE, MONTANA.

DRILL.

1,423,849.

Specification of Letters Patent. Patented July 25, 1922.

Application filed November 21, 1921. Serial No. 516,783.

To all whom it may concern:

Be it known that I, ARTHUR L. HAWKESWORTH, a citizen of the United States, residing at Butte, in the county of Silver Bow 5 and State of Montana, have invented certain new and useful Improvements in Drills, of which the following is a specification.

The present invention has relation to improvements in drills (either rotary or reciprocating) for drilling holes in rock, in the earth, or in any hard substance whatsoever, 10 and consists in the novel features of construction more fully set forth in the specification and pointed out in the claims.

15 The objects of the present invention are: to provide a drill having a detachable bit that is adapted to wedge tightly on the drill shank during drilling operations, but may be readily detached when desired; to provide a 20 drill shank and bit having interlocking means between them which also maintain shank and bit against relative displacement under torsional strains; and to provide a drill having such further and other advantages as will be better apparent from a detailed description of the invention in connection with the accompanying drawings, 25 in which—

Figure 1 is a side elevation of the drill; 30 Fig. 2 is an elevation with the drill turned to present the dove-tail tongue on the shank and groove in the bit for receiving said tongue; Fig. 3 is an elevation with the drill turned to present the side opposite to that shown in Fig. 2; Fig. 4 is a side elevation of 35 the bit detached; Fig. 5 is a side elevation of drill bar or shank with bit removed; Fig. 6 is a detached elevational view of the bit turned to present the dove-tail tongue in end 40 view; Fig. 7 is a detached elevational view of the bit turned to present the dove-tail groove in end view; Fig. 8 is a bottom plan of the bit; and Fig. 9 is an end view of the shank showing the formations that cooperate with 45 those on the bit in end view.

Referring to the drawings, 1 represents a drill-bar or shank provided with a central passage-way or duct α for the flow of water usually employed in drilling operations 50 as well understood in the art. The shank is provided at its bit-supporting end with an inclined tongue 2 tapered toward the outer or bit-supporting end of the shank. The free end of the tongue extends a short distance beyond the axis of the shank, and 55 forms the upper bounding wall of an in-

clined groove 3 tapering toward the base of the tongue, and terminating beyond the shank axis opposite to the tongue. A dove-tail tongue 4 is formed on the upper face 60 h of tongue 2 and extends from the outer edge inwardly and upwardly about one-half the length of said face. The bottom face or outer bounding wall i of the groove 3 has a dove-tail groove 5 (Fig. 5) formed in 65 it, said groove extending downwardly along the face i about one-half its length.

A bit 6 is adapted to be passed across the shank 1, and is provided with formations for cooperating with those on the shank just 70 described, said formations consisting of a tongue 7 and adjacent groove 8 (Fig. 4) complementary to the groove 3 and tongue 2 of the shank. However, the tongues 2 and 7 are made a little shorter than the grooves 75 8 and 3 which receive them so that said tongues will be wedged into said grooves respectively before reaching the end walls of the grooves. Thus when the bit is in place on the shank there will be slight clearance 80 spaces s and s' between tongue 2 and the end of groove 8 and tongue 7 and end of groove 3 respectively.

The bottom face h' of tongue 7 and upper face i' of groove 8 are provided with a dove-tail tongue 9 and dove-tail groove 10 respectively for receiving their complementary groove 5 and tongue 4 on the shank.

The bit 6 is provided with an axially disposed port a' which, when bit and shank are 90 assembled, is in alignment with port a to form a continuous passage through the drill. To assemble the bit and shank the former is passed across the shank so that the tongue 4 enters groove 10 and tongue 9 enters groove 95 5, at which time tongues 2 and 7 will enter grooves 8 and 3 respectively, and as the bit is moved across the shank the faces i' and h' will ride over the faces i and h until the tongues 2 and 7 are wedged in their respective grooves 8 and 3, when further movement 100 will be arrested. Obviously the grooves 5 and 10 extend inwardly toward the axis of the drill farther than tongues 4 and 9, so as not to interfere with the wedging action just 105 described.

By virtue of the faces i , i' inclining toward the ends of the grooves 3 and 8, any pressure on the shank 1 in the direction of the bit, such as results in drilling operations, 110 will cause the bit to wedge even more tightly on the shank. However, when it is desired

to remove a bit for sharpening or other purpose, it is merely necessary to tap against the bit on the side of the open bottom of the groove 8, when it is readily dislodged.

5. The bit is held against rotary movement on the shank under torsional stress by the dove-tail tongues 4 and 9, the side walls of which engage the side walls of the grooves 10 and 5 respectively.

10. Having described my invention, I claim:

1. In combination with a drill bar or shank, a bit movable across the axis of the shank, said bit and drill bar each being provided with an inclined tapering tongue and groove disposed in superposed planes and complementary to the groove and tongue of the opposite member, said tongues and grooves being formed so as to wedge together with vertical pressure along the axis 20 of the drill bar.

2. In combination with a shank, a cutting tool movable across the axis of the shank, said shank and tool each being provided with an inclined tapering groove and tongue 25 and groove complementary to the tongue of the opposite member, said tongues and grooves being formed so as to wedge together with vertical pressure along the axis of the shank, the bottom face of one tongue 30 and the top face of the other tongue each being provided with auxiliary tongues, and the top face of the one groove and the bottom face of the other groove each being provided with grooves complementary to the auxiliary 35 tongues, said last mentioned tongues and grooves operating to hold the shank and cutting tool against torsional displacement.

3. In combination with a shank, a cutting tool movable across the axis of the shank,

said shank and tool each being provided 40 with an inclined tapering groove and tongue and groove complementary to the tongue of the opposite member, said tongues and grooves being formed so as to wedge together with vertical pressure along the axis 45 of the shank, the bottom face of one tongue and the top face of the other tongue each being provided with auxiliary dove-tail tongues, and the top face of the one groove and the bottom face of the other groove each 50 being provided with grooves complementary to the auxiliary tongues, said last mentioned tongues and grooves operating to hold the shank and cutting tool against torsional displacement.

5. In combination with a shank, a cutting tool detachably secured thereto, said shank and cutting tool each terminating in scarfs disposed in superposed planes adapted to cooperate to form a scarf joint, the scarfs of 60 the respective members being formed so as to wedge together on moving one member across the other and in cooperative relation therewith.

6. In combination with a shank, a cutting 65 tool detachably secured thereto, said shank and cutting tool each terminating in scarfs disposed in superposed planes adapted to cooperate to form a scarf joint, the scarfs of the respective members being formed so 70 as to wedge together on moving one member across the other and in cooperative relation therewith, and means for holding the cutting tool against displacement laterally with respect to the tongues.

In testimony whereof I hereunto affix my signature.

ARTHUR L. HAWKESWORTH.
